RUG MACHINE

George H. Morrow, Portland, Oreg.

Application March 26, 1934, Serial No. 717,293

5 Claims. (Cl. 112—80)

My invention relates to improvements in rug making or turfing machines, having for its particular objects, simplification, inexpensiveness of manufacture and improvements of operation.

5 Essentially the invention embodies a bifurcated or forked frame formed of two alike side members or legs, spacedly held in parallel relationship by an intervening end or handle member. Between the legs is mounted a reciprocating needle together with the mechanism for imparting such movement thereto, together with an improved guide for the needle which is readily adjustable to regulate the spacing or distance between needle strokes.

10 15 One of the principal objects of the invention is to provide a rug machine which is simple, easy and inexpensive to manufacture.

Another object of the invention is to provide improvements in the needles of rug making or turfing machines, whereby the turf or loops are all of the same length, preventing the pulling of such loops, and avoiding an unevenness or irregularity in the pile of the finished product.

20 25 A further object of the invention is to provide an improved needle guide, one which is easily adjusted for regulating the distance or spacing of the needle travel over the fabric operated upon, the distance between strokes.

30 A continued object of the invention is to provide a device of this character constructed of such few and simple parts that the average person may readily understand and operate it.

Further objects and purposes of the invention will be ascertained upon reading the specification following, assisted by the accompanying drawing, wherein:—

Figure 1 is a perspective of the invention.

Figure 2 is a fragmentary, rear elevation, partially in section, of the invention.

40 Figure 3 is a fragmentary perspective illustrating the adjustable needle guide.

Figure 4 is an elevation of a needle employed in the invention.

Figure 5 is a perspective of the needle guide.

45 Figure 6 is a side elevation, illustrating the invention in operation.

Similar characters refer to similar parts throughout the several views.

In the drawing, my invention will be seen as 50 consisting of a frame 1 formed of two alike and interchangeable side members or legs 2 secured to an intervening spacer 3. Members 2 are somewhat elongated and are secured to opposite sides of spacer 3 by any suitable means such as 55 the screws 4. Members 2 and 3 may be of any

material suitable for this purpose. As will be seen spacer 3 is considerably shorter than side members 2, this being in order to provide a space 5 between such side members which extends the major portion of their length. The end of frame 1 where legs 2 and spacer 3 are joined constitutes the handle portion of the device.

The lower end of each leg 2 has an elongated guide carrying slot 6. These slots are identical in each leg and extend lengthwise thereof. On the outer face of each leg in the region of the slot 6 are cut or otherwise indented notches 7. Slots 6 and notches 7 are for holding and positioning a guide hereinafter described. The lower ends 8 of legs 2 are treads or feet, and frame 1 is held upright upon such feet while being operated.

The invention employs a hollow or cylindrical needle 9 provided with a shank or pitman upper portion 10 terminating in a bearing slot 11 opening through one edge of such pitman. This seats upon crank 13 of crankshaft 12. A slide 11a, movable back and forth on pitman 10, is provided with a finger 11b which may be slid over the opening into slot 11, closing it and prohibiting the needle from becoming detached. The foregoing permits of ready exchange of needles, thereby permitting different sizes of needles to be employed. Crankshaft 12 has bearings or spindles 14 and 15, and an operating crank and handle 16 and 17 respectively. Spindles or bearings 14 and 15 are rotatably carried in legs 2, as indicated in Figure 2, with needle 9 operatively connected to crank 13 as heretofore indicated. In order to maintain needle 9 in its proper operative position, and to properly guide it in its operation, a suitable guide 18 is provided. Guide 18 consists of a central or guide portion 19 having an aperture 20 in which needle 9 operates as particularly shown in Figure 3. Extending from opposite sides of the central portion 19 are radially projecting portions or arms 21 terminating in cross members or heads, or stops 22. Members 22 and 21 together form T-shaped arms projecting from the central portion 19. The arms 21 extend through slots 6 of legs 2 with heads 22 bearing upon the outer faces thereof. Each head 22 extends across a slot 6, and the heads being longer than the width of such slots, they cannot pass therethrough unless member 18 is turned axially ninety degrees. The normal condition of the heads, as shown in the drawing, is transversely over such slots.

The inner faces of the heads 22 are V-shaped at 23 to enable them to seat in notches 7 which

70 75 80 85 90 95 100 105 110

70 75 80 85 90 95 100 105 110

70 75 80 85 90 95 100 105 110

70 75 80 85 90 95 100 105 110

70 75 80 85 90 95 100 105 110

70 75 80 85 90 95 100 105 110

are likewise V-shaped. The distance between the inner faces 23 of heads 22 is less than the distance between the outer faces of legs 2, therefore, when guide 18 is in the position shown, legs 2 are sprung together somewhat, as will be seen in Figure 2. The urge of the legs 2 to unspring or assume normal position causes them to press against the V-faces, thus holding such faces in the notches 7, and consequently the member 18 against shifting. In Figure 2 it will be noted that there are more than one notch on each leg, there being six in this instance, one above the other. This provides for six positions in which member 18 may be positioned. The vertical position of guide 18 governs the spacing or length of the stitches made by needle 9. Needle 9 fulcrums on guide 18, hence when guide 18 is maintained in the uppermost notches 7, the lower or penetrating end of needle 9 rocks its greatest distance, while the reverse is true when guide 18 is held by the lowermost notches, and the intermediate notches provide for altering the rock of the needle to intermediate degrees.

As before stated needle 9 is hollow or cylindrical, and the thread or yarn used by the machine is threaded therethrough. To this end an opening 24 is provided in the intermediate body portion of the needle. The lower end of the needle is cut away on one side as indicated at 25, and inwardly curved from the point or region 26 to its lower end, thus providing the penetrating point 27. Yarn 28 is threaded through opening 24 into and through the body of the needle and out through the cut away portion 25. An eye 29 is provided in the curved end of the needle, and the yarn passing out of the cut away portion 25 is passed therethrough. After this has been done the needle is ready for operation.

In operation, the machine is used in conjunction with pattern lines delineated upon a fabric, such as burlap. The machine is held upright by the handle with the feet 8 astraddle of the line to be followed. Crank 16, by means of handle 17, is operated. This causes the needle to alternately penetrate and recede from the fabric. As it penetrates the fabric it carries the yarn therethrough, and as it recedes it leaves yarn in the form of loops 30, as shown in Figure 6, on the side of the fabric opposite to which the machine is operated. The needle by reason of the fulcrum established in the member 18, recedes from the fabric to the rear of legs 2, as shown by the dotted outline in Figure 6, and enters the fabric forwardly of such legs, as shown by full line in Figure 6. Thus as it alternately enters and recedes it propels the machine along the line on which it is being operated as indicated by the arrow in Figure 6.

Oftentimes in devices of this character, the needles have a tendency to retract the yarn, thus causing an irregularity in the length of yarn loops. This is caused by the yarn being pressed against the sides of the needle and being withdrawn therewith. This fault is overcome in the construction of the present needle. Needle 9 penetrates the fabric 31 to approximately the point 26 where its lower curvature commences. Therefore, by reason of such curvature, its width decreases as it is being withdrawn, and the pressure against the yarn or frictional pull decreases, leaving the loop undisturbed on the underside of the fabric 31.

I claim:—

1. In a rug machine, a bifurcated frame formed of a pair of spaced legs secured to a handle member at their upper ends and provided with elongated slots extending longitudinally thereof proximate their lower ends, a loop forming needle operatively mounted between said legs, a guide through which said needle operates, arms projecting from said guide and extending through the aforesaid slots, cross members on the outer ends of said arms engaging the outer faces of said legs, and notches formed in the outer faces of such legs to intersect the aforesaid slots forming seats for the aforesaid cross members. 80

2. In a rug machine, a bifurcated frame formed of a pair of spaced legs secured to a handle member at their upper ends and provided with elongated slots extending longitudinally thereof proximate their lower ends, a crankshaft rotatively mounted between said legs, a loop forming needle operatively connected to said crankshaft, a guide through which said needle operates, arms projecting from said guide and extending through the aforesaid slots, cross members on the outer ends of said arms extending over the outer faces 100 of said legs, and seats in the outer faces of such legs in which said cross members are adapted to seat. 95

3. In a rug machine, a bifurcated frame formed of a pair of spaced legs secured to a handle member at their upper ends and provided with elongated slots extending longitudinally thereof proximate their lower ends, a crankshaft rotatively mounted between said legs, a loop forming needle provided with a shank upper end, a notch bearing in the upper end of such shank adapted to seat upon the crank of such crank shaft, a slide upon said shank, a finger projecting from said slide and adapted when said slide is moved upwardly to cover the opening into said notch bearing and 115 prevent the removal thereof from said crank, a guide through which said needle operates, arms projecting from said guide and extending through the aforesaid slots, cross members on the outer ends of said arms extending over the outer faces 120 of said legs, and seats in the outer faces of such legs in which said cross members are adapted to seat. 105

4. The herein described frame embodying spaced legs having slots in their lower ends and the needle guide associated therewith provided with portions extending through said slots and terminating in cross members seating upon the outer faces of said legs. 125

5. In a rug machine, a pair of alike legs secured at their upper ends in spaced relationship with each other and provided with slots proximate their lower ends, a loop forming needle operatively mounted between said legs, a guide through which said needle operates, arms projecting from 135 said guide and extending through the aforesaid slots, cross members on the outer ends of said arms engaging the outer faces of said legs, the length of such arms being less than the distance between the outer faces of said legs thereby 140 springing such legs toward each other whereby the unspringing urge of the legs causes them to press against said cross members, and notches forming seats for the aforesaid cross members formed in the outer faces of said legs in the region 145 of the aforesaid slots. 130

GEORGE H. MORROW.
